UNITED STATES PATENT OFFICE.

JOHN W. BROWN, OF NEW YORK, N. Y.

LETTER-BOX.

Specification forming part of Letters Patent No. 34,940, dated April 15, 1862.

To all whom it may concern:

Be it known that I, JOHN W. BROWN, of the city, county, and State of New York, have invented a new and Improved Letter-Box for the Post-Office Department and Designed for City Use in Streets; and I do hereby declare that the following is a full, clear, and exact description of the same, reference being had to the annexed drawings, making a part of this specification, in which—

Figure 1 is a vertical central section of my invention, taken in the line *xx*, Fig. 3; Fig. 2, the same view as Fig. 1, showing the movable parts in a different position. Fig. 3 is a section of same taken in the line *yy*, Fig. 1; Fig. 4, a detached face view of a toothed or serrated edge of an opening of same.

Similar letters of reference indicate corresponding parts in the several figures.

This invention relates to a new and improved letter-box of that class which is attached to lamp-posts or other convenient fixtures in streets to receive letters for the general post-office.

The object of the invention is to obtain a box which will admit of the letters being deposited in it with great facility, and from which they cannot be illegitimately abstracted, and still be exceedingly simple in construction, not liable to get out of repair, nor capable of being choked or clogged, so as to be rendered inoperative by the insertion of packages or parcels of undue size.

To enable those skilled in the art to fully understand and construct my invention, I will proceed to describe it.

A represents the upper part of a box, which may be of any convenient size, and *B* is a hollow cylinder, which is attached to the upper part of the box *A*, and communicates with the interior of *A* by an opening *a*. The cylinder *B* also has an opening *b* made in its upper part, the use of which will be presently explained. The cylinder *B* has a semi-cylinder *C* fitted on it. The semi-cylinder *C* is movable or is allowed to turn on an axis, which is formed of two pins or journals *c c*, which pass through the centers of the ends *d d* of the cylinder *B*, the latter being stationary. The semi-cylinder *C* is loaded or has weights attached, so as to keep it in the position shown in Fig. 2, which position, it will be seen, covers the hole or opening *b* in the cylinder *C*. One

function, therefore, of the semi-cylinder is shown.

Within the cylinder *B* there is placed another cylinder *D*, which has the pins or journals *c c* for its axis. The semi-cylinder *C* and cylinder *D*, therefore, have a common axis, and they are connected by pins *e e*—one at each side—which pins pass through curved slots *ff* in the ends *d d* of cylinder *B*. The curved slots *ff* admit of the inner cylinder *D* and semi-cylinder *C* turning a distance equal to the length of the slots. The inner cylinder *D* has two fixed partitions *g g'* within it, which form a central chamber *E*, one end of which is open, as shown at *h*. The chamber *E* is equal in width to the length of the cylinder *D*, and the length or depth of the former is equal to the diameter of the latter.

Within the chamber *E* there is a flap or valve *F*, which extends the whole length or depth of the chamber and has its back end secured in the chamber by pivots *i i*. The flap or valve *F* has a pin *j* attached to each side of it, and these pins pass through curved slots *kk* in the ends *ll* of the inner cylinder *D*, and also pass through curved slots *mm* in the ends *d d* of the cylinder *B*, the slots *mm* being concentric with the slots *ff*, as shown clearly by the dotted lines in Figs. 1 and 2.

The operation is as follows: In order to deposit the letter in the box *A*, the operator turns the semi-cylinder *C*, so as to expose the opening *b* in cylinder *B*, and by so doing brings the open end *h* of the chamber *E* in line with the opening *b* in cylinder *B*, as shown in Fig. 1. The package or letter is inserted in the chamber *E* and the operator releases the semi-cylinder *C*, which, with cylinder *D*, turns back to its original position, the former covering the opening *b*, and the open end or mouth of chamber *E* coming in line with the opening *a*, so that the package or letter will drop from chamber *E* into box *A*.

The flap or valve *F* performs an important function, as follows: When the mouth *h* of chamber *E* is in line with the opening *b*, the flap or valve *F* is about parallel with the lower side or partition *g'* of the chamber, and the flap or valve cannot be moved farther outward or upward from said side or partition, as the pins *j* are restricted in their upward movement by the slots *mm*. The flap or valve *F*, therefore, determines or limits the

dimensions of the chamber E when the latter is in a position to receive the package or letter. When, however, the chamber E reaches its discharging position, the flap or valve F is at liberty to move outward from the side or partition g' a distance equal to the length of the slots $k k$, (see Fig. 2,) and the chamber E being thereby enlarged the package or letter drops freely from it. Thus it will be seen that the chamber E cannot become choked or clogged by pressing packages or bundles of letters in E, for the dimensions of the latter may, by means of the flap or valve F, be increased when in a discharging position.

The lower opening a of the cylinder B has a toothed or serrated edge n at its front side. This notch or serrated edge extends the whole width of said opening (see Fig. 4) and serves to prevent letters or packages being abstracted from the box A by means of a hook and line, for the serrated edge will catch the package or letter as the latter is drawn up (see dotted lines in Fig. 2) and prevent it from passing into chamber E. The hook, it will be understood, may be introduced into box A by inserting it in chamber E and allowing the latter to turn down to its discharging position.

I would remark that the lower part of the hollow cylinder B at each end of its opening a may have a pendent flap or valve a^x attached to it, said flaps or valves extending downward within box A and serving as additional guards

to prevent the abstraction of letters from the box. These flaps or valves would in a majority of cases serve as an obstruction to the raising of a letter by means of a hook and cord, as the letter in being drawn up would catch against their lower edges and the valves would close by the raising of the letter. To insure this result, the valves are not allowed to assume a vertical but a slightly-inclined position, in consequence of bearings b^x directly behind them. (See Figs. 1 and 2.) These valves, however, may be used or not, as desired.

I do not claim separately any of the within-described parts; but

I do claim as new and desire to secure by Letters Patent—

1. The valve F, in combination with the chamber E, cylinder D B, and semi-cylinder C, the cylinder B being provided with the openings $a b$, and all arranged for joint operation, as and for the purpose herein set forth.

2. The toothed or serrated edge n of the opening a of cylinder B, when used in connection with the semi-cylinder C, and cylinder D, provided with the chamber E and valve F, for the purpose specified.

J. W. BROWN.
